UNITED STATES PATENT OFFICE.

LEONORR L. PARK, OF ST. LOUIS, MISSOURI.

WASHING MACHINE.

Application filed August 9, 1922. Serial No. 580,813.

To all whom it may concern:

Be it known that I, LEONORR L. PARK, a citizen of the United States, residing in the city of St. Louis and State of Missouri, have 5 invented certain new and useful Improvements in Washing Machines, of which the following is a specification.

This invention relates to dish washing machines and has for its object to provide a 10 machine of such class, in a manner as hereinafter set forth, with means for circulating water through the machine during the operation thereof and further for filtering the water thereof during the washing thereof 15 for separating the garbage, grease, etc., therefrom.

A further object of the invention is to provide a machine of such class, in a manner as hereinafter set forth for circulating water 20 through the machine during the operation thereof and further for filtering the water, during the washing operation, to separate the grease, garbage, etc., therefrom, and further for causing the discharge of the grease, 25 garbage, etc., from the machine and which has been separated from the water during the circulation thereof.

A further object of the invention is to provide a dish washing machine, in a manner as hereinafter set forth, with means for heating the water within the machine during 30 the washing operation, and further for drying the dishes at the completion of the washing operation, after the water has been 35 drawn off.

A further object of the invention is to provide a machine of such class, in a manner as hereinafter set forth, with a removable and rotatable element for supporting 40 the dishes during the washing operation, and further, whereby the dishes can be positioned in said element, whether the latter remains within or is removed from the machine.

A further object of the invention is to provide a machine of such class, in a manner as hereinafter set forth, with a rotatable supporting element for the dishes to be cleaned and further, with means for spraying 45 the dishes supported by said element, with water to rinse them, whether the said supporting element, is rotating, or is held stationary.

Further objects of the invention are to 50 provide a dish washing machine which is

simple in its construction and arrangement, strong, durable, compact, efficient and convenient in its use, readily assembled, and comparatively inexpensive to manufacture.

With the foregoing and other objects in view, the invention consists of the novel construction, combination and arrangement of parts, as hereinafter more specifically described, and illustrated in the accompanying drawings, wherein is shown an embodiment 60 of the invention, but it is to be understood that changes, variations and modifications can be resorted to which come within the scope of the claims hereunto appended.

In the drawings wherein like reference characters denote corresponding parts throughout the several views:—

Figure 1 is a top plan, partly broken away, of a dish washing machine in accordance with this invention,

Figure 2 is a front elevation, partly in section, of the machine,

Figure 3 is an end view,

Figure 4 is a transverse section,

Figure 5 is a vertical sectional view illustrating the filtering element.

Referring to the drawings in detail, the machine includes a tank element comprising a top frame formed with a pair of opposed longitudinally extending bars 1, and a pair 85 of opposed transversely extending bars 1'. The ends of the said bars 1, 1' are bevelled to provide for a close fit, at the corners between the said bars, and the bars 1, 1', at the outer corners of the top frame are secured together by angle shape stay members 1''. Projecting from the other side of the top frame is an auxiliary frame comprising a pair of longitudinally extending bars 1^a and a transversely disposed bar 1^b. The 90 bars 1^a and 1^b abut against the inner horizontal bar 1' and are maintained in abutting relation, with respect to the inner horizontal bar 1', by straps 1^c, which are secured to the longitudinal bars 1 and 1^a, by the hold-fast 95 devices 1^d. The longitudinal bars 1^a, are secured to the transverse bar 1^b, by angle-shape stay members 1^e, which are positioned at the corners of the auxiliary frame. The strap 1^c and hold-fast device 1^d, not only 100 maintain the longitudinal bars 1^a, against the inner transverse bar 1', but also fixedly secures the said inner transverse bar 1', against the longitudinal bars 1. The top 105 frame, as well as the auxiliary frame, which

forms a part of the top frame, is supported by two pair of outer standards 1^e and 1^f, and a pair of intermediate standards 1^g. The standards 1^e and 1^f, are secured to the top and auxiliary frames by the stay pieces 1^h and 1ⁱ respectively. The standards 1^g are secured to the top frame, by the straps 1^c. Longitudinal and horizontal braces 1ⁿ and 1ⁱ, are secured to the standards, as at 1^m and 1ⁿ respectively. The bars of the top and auxiliary frame, as well as the standards are constructed of angle iron, and secured against the inner faces of the standards 1^e, 1^g, and further against the inner faces of 15 the bars 1 and 1', is a receptacle 2, having a concave bottom 2', and which provides in connection with the standards, a tank, forming a chamber 2^a. The inner and outer end walls of the chamber 2^a are indicated at 2^b, 20 2^c, respectively. A removable flanged cover 3 is provided for the tank, and has secured to its upper face a pair of hand-grips 4.

Secured to the outer face of the bottom of the tank, as well as depending therefrom, 25 is a semi-circular member 5, and which has its major portion thereof, spaced from the bottom of the tank, to provide in connection with the said bottom, a heating chamber 5^a. The member 5, at its upper portion, and at 30 opposite sides, is provided with vent openings 6, the chamber 5^a has crescent-shaped end walls 5^b, which are an integral part of member 5 and abut against the outer face of the bottom of the tank. The member 35 5 is of a length equal to the length of the tank and has the longitudinal marginal portions of its inner face abutting throughout against the outer face of the tank.

Supported by the end walls 5^b of the 40 chamber 5, and extending entirely through said chamber 5, is a gas burner 7, having its outlet ports 7^a directed against the bottom of the tank.

The burner 7 is spaced from the bottom 45 of the tank and projects outwardly through one of the walls 5^b, and carries a mixing chamber 8, having connected therewith a gas supply pipe 9, formed with a cut-off 10.

The machine further includes a supporting element for the dishes to be washed, and which consists of a pair of circular disks 11, 11^a, which are connected together by spaced tie bolts 19, positioned in close proximity to the inturned edges 11^b of the 55 disks 11, 11^a, and secured in position by the nuts 11^c. The tie bolts 19 form the body of said element, and as they are arranged in spaced relation with respect to each other, a skeleton supporting element is provided.

Hinged as at 12', to one of the tie bolts 19, is an imperforate cover 12, which is 60 arcuate in contour and is detachably connected to another of the tie bolts 19, that is to say a tie bolt 19 opposite to that bolt 65 to which the cover is hinged, by a suitable

latching element 14. Secured to that tie bolt 19, to which the cover is hinged, and to the other tie bolt 19 to which the cover is latched, is a foraminous member 15, which in connection with the cover 12, provides a compartment 16 for holding silverware or small dishes.

Arranged within the supporting element, as well as being positioned in spaced relation with respect to each other, is a series 75 of dish holders 17, and each of which is in the form of an elongated coil constructed from a suitable length of wire, and each end of the lengths of wire, is bent diametrically as at 17^a, with respect to the coil, and extends through an eye or fastener on the inner face of a disk 11 or 11^a, and under such conditions the holders are supported at their ends from the disks 11 and 11^a, as well as being connected to these latter. Each of 80 the holders 17, is furthermore provided with a spring clip 20, for the purpose of connecting the holder to a tie bolt 19 and which will assist in connection with the disk 11, 11^a for supporting the holders in position. 90

The disk 11, centrally thereof, on its outer face, has secured thereto by hold-fast devices 20^a, a hub 21, in which is adapted to extend a shaft 23, provided with threads 23^a, and the said shaft 23, has threaded engagement with the threaded bore of a pair of opposed apertured flanged supporting members 22, which are secured against the faces of the end 2^b of the receptacle 2, by the hold-fast devices 22^a. The walls of the 100 openings of the supports 22, are threaded for engagement therewith of the threads of the shaft 23, and the latter has a handle 24 on its outer end, for the purpose of adjusting it for engagement in the hub 21, when occasion requires.

Secured to the outer face of the disk 11^a, by the hold-fast devices 25^a, is a support 25, having an outwardly projecting squared shank 26, and which extends into a polygonal-shaped socket formed on the inner end of a driven shaft 29. A collar 27, is fixed to the inner end of the driven shaft 29 and the latter is operated by a drive shaft 29^a. A flanged bearing element 28 is fixed to the 110 inner face of the end 2^c of the receptacle and through which extends as well as projects inwardly therefrom the driven shaft 29. The shaft 29^a is mounted in a bearing 28, which is secured to the inner face of the 115 end 2^c, of the receptacle 2, by the hold-fast devices 28^a.

By providing means for uncoupling and coupling the shaft 29, to and from the shaft 29^a, a means is provided for rotating, and 120 discontinuing the rotation of the supporting element, and by this arrangement the dishes within the supporting element, can be sprayed to rinse them, when the supporting element is stationary. The construction for 125 130

the spraying of the dishes within the supporting element will be hereinafter referred to.

The shaft 29^a, as well as the clutching mechanism 30, and part of the shaft 29, are arranged in the auxiliary frame, and the said shaft 29^a, further projects outwardly from said auxiliary frame, and is provided on its outer end with an enlarged gear wheel 31, having one face thereof formed integral with, or attached thereto, a driving pulley 32, which is connected by an endless belt 34, to a pulley 34^a, on the outer end of the shaft 34^b of the motor 35, which is supported 10 at the lower portions of the standards 1^f, 1^g, and upon the brace 1^l. The gear wheel 31, has a handle 33, for use, when desired, to operate said gear 31 manually. The said gear 31 meshes with a pinion 36, carried by 15 the operating shaft 36' of a pump 37, which is mounted on a support 37^a. The pump 37 is of the centrifugal type.

Arranged on the support 37^a is a filter consisting of a vertically disposed cylinder 43, having an inverted cone-shaped bottom 43^a, provided with an outlet 43^b, to which the discharge pipe 50 is secured, the latter depends downwardly, and is connected preferably to a sewer, or communicates with any 20 suitable collector for receiving the matter discharged through said pipe 50. Arranged within the cylinder 43, is a vertically disposed filtering element 45, as shown constructed of a foraminous member of close 25 mesh, and said member 44 conforms in contour to the cylinder 43. Lugs 46 are formed on the inner face of the cylinder 43, at the upper and lower portions thereof, and provide means for holding the filtering element 30 45 in position. The lugs 46 space the element 45 from the inner face of the cylinder 43, as indicated at 44. The cylinder 43 is provided with a removable handle member 48, and leading to the cylinder 43, as well 35 as communicating therewith, is an intake pipe 49, for fresh water. The lower end of the cylinder 43 has an inlet 42^a, and opening therein, is an outlet pipe 42, which extends from the tank chamber 2^a. Leading from 40 the cylinder 43, as well as communicating therewith, is a pipe connection 38, the latter opens into the pump 37. The screen 45 serves as a partition diametrically dividing the cylinder 43 so that water drawn in 45 through inlet 42^a is filtered before being drawn through the pipe 38 to the pump 37.

Extended inwardly from one of the longitudinal bars 1, of the tank frame, is a pair of hangers 41, which support a longitudinally extending sprinkler pipe 40, having the outlet ports thereof directed downwardly for the purpose of spraying water into the supporting element, in a direction as indicated at 41^a, Figure 4. The sprinkler 50 pipe 40 is connected to a vertical pipe 40^a,

which leads from the pump 37, so that during the operation of the pump, when the water is circulated through the tank, the supply of water to the tank will be had by spraying it from the pipe 40. The pipe 40 70 extends through the end 2^a of the tank.

From the foregoing description, taken in connection with the accompanying drawings, a construction of dish washing machine is set up, having means for heating the water during the circulation thereof through the tank, or when the water is not circulating, and further provides means whereby the dishes in the supporting element can be sprayed with water, whether the said element is rotating or not, and it furthermore provides means whereby the circulated water is freed of grease, garbage, etc., after it leaves the tank and before it is re-supplied thereto. The construction also permits of the entire removal of the supporting element so as to rack or remove the dishes, or permits of the removal or racking of the dishes when the supporting element remains within the tank.

The burner element, provides means for not only heating the water for facilitating the cleansing operation but furthermore provides means for drying the dishes after the cleansing operation has been completed and the water withdrawn from the tank.

What I claim is:—

1. A dish washing machine comprising a tank, a filtering element exteriorly thereof, a pipe leading from a source of supply and opening into said element near the top thereof, a pump exteriorly of the tank, a pipe connection leading from one side of the bottom of the filtering element to the pump, means extended from the pump and opening into said tank near the top thereof for supplying a cleansing medium thereto, a pipe connection leading from the bottom of the tank to the other side of the bottom of the filtering element whereby on the operation of the pump the cleansing medium from the supply and from the tank will be filtered and circulated through the tank, and an outlet depending centrally from the bottom of said filtering element.

2. A dish washing machine comprising a stationary tank, a spray pipe extending lengthwise and near the top thereof and projecting from one end of the tank, a revolvable article carrier suspended within the tank, a filter exteriorly of the tank, means for establishing communication between the bottom of the tank and one side of the bottom of said filter, a cleansing medium supply pipe leading to the upper portion of the filter, a pump communicating with the other side of the bottom of the filter, a vertical pipe connection between the pump and the projected end of the spray pipe, a discharge pipe depending from the bottom of the filter,

a driving mechanism for said carrier, and means for driving the pump from said driving mechanism simultaneously with the driving of the support.

- 5 3. A dish washing machine comprising a rectangular support, a tank secured therewith and having its outer end spaced from the outer end of the support, a revolvable article carrier suspended within the tank
10 and spaced from the ends thereof, a filter mounted on the support exteriorly of the outer end of the tank, a pump mounted on the support exteriorly of said end of the tank, a motor mounted on the support exteriorly of said end of the tank and below
15 said pump and filter, a driven element

mounted on the support and extending through said end of the tank and detachably engaging with the carrier for revolving the latter, means extending through the other 20 end of the tank and detachably engaging with the carrier for revolvably supporting it, a driving connection between the said element and said pump, a driving connection from the motor to said element, and 25 pipe connections to provide for the circulating of a cleansing medium through the filter, pump and tank.

In testimony whereof, I affix my signature hereto.

LEONORR L. PARK.
